UNITED STATES PATENT OFFICE

2,673,058

ELECTRIC CAN OPENER

Wayne H. Tyler, Tucson, Ariz.

Application February 1, 1950, Serial No. 141,667

4 Claims. (Cl. 248—313)

1

This invention comprises novel and useful improvements in an electric can opener and more specifically pertains to a power operated device for rotatably supporting a can and for rotating the can against a stationary cutter blade, together with means for holding the severed can top.

The primary objects of this invention are to provide in a power operated can opener, improved facilities for supporting and journaling the can and for rotating the same against a stationary cutter blade; to retain the severed head of the can; to readily accommodate different sizes of cans; and to reduce the friction and enhance the efficiency of operation of the can opener.

The objects of the invention are attained by a can opener consisting of a supporting base having a supporting standard rising therefrom, means for adjustably securing a stationary cutter head to the standard; a relatively fixed abutment vertically adjustable upon the standard and having anti-friction means for engaging the side of a can; a movable abutment slidably adjustable upon the base and having anti-friction means for engaging the opposite side of a can; anti-friction means supporting the bottom of a can; together with improved means for rotating a can when held between the fixed and movable abutments.

These, together with various ancillary features and objects of the invention which will later become apparent as the following description proceeds, are attained by the present invention, a preferred embodiment of which has been illustrated by way of example only in the accompanying drawings, wherein:

Figure 1 is a side elevational view showing a preferred construction of can opener embodying the principles of this invention, a can being shown in position in the opener for removal of its head;

Figure 2 is a vertical central sectional view taken substantially upon the plane indicated by the section line 2—2 of Figure 3 and illustrating certain details of the cutter head, the reduction gearing thereof and the fixed and movable abutments forming a part of the invention, a can being shown in dotted lines in the device;

Figure 3 is a horizontal sectional view taken substantially upon the plane indicated by the broken section line 3—3 of Figure 2 and illustrating certain details of construction of the reduction gearing;

Figure 4 is a horizontal sectional view taken substantially upon the plane indicated by the section line 4—4 of Figure 2;

Figure 5 is a fragmentary end view of the base of the opener, showing certain details of the mounting of the movable abutment thereon;

Figure 6 is a vertical sectional view taken substantially upon the plane indicated by the section line 6—6 of Figure 7 and showing certain details of the locking means for adjustably securing the movable abutment to the base of the device; and

Figure 7 is a fragmentary vertical sectional view taken substantially upon the plane indicated by the section line 7—7 of Figure 3 and showing further details of the construction and mounting of the movable abutment upon the base of the device.

Referring now more specifically to the accompanying drawings, wherein like numerals designate similar parts throughout the various views, attention is directed first to Figures 1 and 2, wherein it will be seen that the apparatus illustrating the principles of this invention preferably comprises a flat plate-like base 10 of any suitable character, which is provided with a vertical supporting standard 12 which may be conveniently in the form of a rod or tubular member. Slidable upon the standard 12 and adjustably secured in vertically adjusted position thereon, is a cutter head assembly indicated generally by the numeral 14.

Likewise vertically adjustable upon the standard 12, is a fixed abutment 16 while a movable abutment 18 is adjustably secured upon the base plate 10 and cooperates with the fixed abutment for rotatably retaining therebetween a can 20 which the device is intended to open.

Referring now to Figure 4, it will be seen that the base 10 has its upper surface recessed to receive a plurality of anti-friction members 22, which may conveniently be in the form of cylindrical rollers or the like whose upper portions extend upwardly above the base 10, these rollers being disposed so as to receive and support the bottom of the can 20, as will be apparent from Figures 1, 2 and 4.

The fixed abutment may conveniently comprise a plate-like body or bracket 24 having a hub portion or sleeve portion 26 which is slidably received upon the standard 12. Secured to or if desired formed as integral part of the plate 24, is an arcuately shaped member 28 having a concave cylindrical surface which is suitably slotted as at 30 and has retained therein in any suitable manner a plurality of anti-friction cylindrical bearing rollers 32 which extend inwardly of the concave surface and are adapted to rotatably engage and support the side of the can 20.

The movable abutment 18 likewise includes a similarly shaped arcuated member 34 which is likewise provided with the anti-friction rollers 36, the members 34 and 28 being adapted to embrace the opposite sides of the can 20 and by means of the anti-friction elements 32 and 36, in conjunction with the elements 22, support and retain the can for rotational movement about its longitudinal axis.

The movable abutment 18, as will be more apparent from Figures 5-7, includes a supporting block or bracket 38, which slides upon the upper surface of the base 10 and is provided with a depending, wedge-shaped slide 40 which is retained for sliding movement lengthwise of a dovetailed shaped channel 42 formed in the base 10, this channel having upwardly and inclined side walls 44. Since this channel opens to the end of the block, as shown in Figures 2 and 3, it will be seen that the movable abutment can be mounted upon the block by endwise insertion of the depending slide 40 in the open outer end of the channel 42. Preferably the channel is disposed in alignment with the standard 12 so that the movable abutment may be moved toward and from the stationary abutment and the standard 12.

A novel and advantageous means is provided for selectively locking the movable abutment to the channel 42 in longitudinally adjusted positions thereon. For this purpose, the member 33 is provided with a slot opening from its upper surface to its lower surface, and a pair of clutch levers 46 and 48 extend through this slot and are pivotally connected to each other and to the member 38 as by a transversely extending pivot pin 50, these clutch members having clutch jaws 52 and 54 on their lower ends which extend within the channel 42 and are engageable with the inclined side walls thereof. As shown best in Figure 5, a resilient means such as a compression spring 56 yieldingly urges the clutch levers and consequently the clutch jaws into engagement with the inclined walls to thereby frictionally lock or engage the movable abutment in adjusted position upon the base 10.

Referring now to the cutter head assembly 14, it will be seen that the latter includes a casing or housing 58, having a flat horizontally extending lower surface 60, to which is detachably secured a permanent magnet 62 of any desired character for magnetically retaining the top of a can when the latter has been cut from the can by the operation of this device, and to which is further secured the base portion 64 of a depending can opener or knife blade 66.

A tapered or conical toothed roller 68 is provided for gripping the edge or rim of a can and rotating the same against the stationary cutter 66, this roller being provided with an axle 70 which extends through the bottom wall 60, being journaled therein in any suitable manner, and is provided with a gear 72 within the housing 58.

As will be apparent from Figures 2 and 3, a reduction gearing is provided within the housing 58 for rotating the gear 72 and the roller 68. This reduction gearing includes a gear 74 meshing with the gear 72, the gear 74 having a coaxially disposed gear 76 rigidly associated therewith. The gears 74 and 76 may conveniently be fixedly secured to a common shaft 78 as will be apparent from Figures 2 and 3. The gear 76, in turn, meshes with a worm gear 80 which is fixedly secured to a shaft 82 having one extremity journaled in a supporting bracket 84 mounted upon the interior of the housing 58. The other end of

the shaft 82 may be detachably secured to or if desired may form an integral part of the armature shaft of an electric motor indicated generally by the numeral 86, and which may be of any desired character, being provided with a customary speed controlling switch 88, and being electrically connected to any suitable source of electric power such as by electric cables 90.

The entire cutter head assembly, including the electric motor 86 which is detachably secured to a flange upon the cutter head assembly, as by fastening screws 92, is adjustably slideable upon the standard 12. For this purpose, the housing 58 is provided with a vertically extending tubular portion 94 which constitutes a sleeve slideable upon the standard 12 as shown in Figures 1 and 3. Adjacent its upper end, this sleeve is provided with a laterally extending housing 96 having a lateral bore 98 therein opening into the bore receiving the standard 12. A pair of locking levers 100 and 102 are pivotally mounted in the lateral bore 98, as upon pivot pins 104 and 106, and are provided with toothed jaws 108 and 110 which are adapted for wedging engagement upon the surface of the standard 12. A suitable compression spring 112 yieldingly urges the levers 100 and 102 away from each other or in position to wedge the jaws against the standard, whereby the cutter head may be locked in vertically adjusted position.

The fixed standard 24, above mentioned, may be adjustably mounted upon the standard 12 by the same type of clutch construction just described with respect to the cutter head. Such a construction has been indicated in Figures 1 and 2, wherein the clutch levers 100 and 102 have been indicated.

From the foregoing, the construction and operation of the device will be readily understood and further explanation is believed to be unnecessary.

40 It will be seen that the apparatus will accommodate readily different sizes of cans, will rotatably support the base of the can, and will rotatably retain the sides of the can while the same are being revolved against a stationary cutter blade.

45 It is not intended to limit the invention to the exact construction shown and described, but all suitable modifications and equivalents may be resorted to, falling within the scope of the appended claims.

50 Having described the invention, what is claimed as new is:

1. A can opener comprising a base, means for rotatably supporting a can upon said base, said supporting means including a fixed abutment having a cylindrical concave face for receiving the side of a can, a standard on said base, said fixed abutment being vertically movable upon said standard, locking means for retaining said fixed abutment in vertically adjusted position on said standard, said locking means comprising a pair of levers pivoted to said fixed abutment, toothed jaws on said levers wedgeably engageable with said standard and resilient means urging said jaws into wedged engagement with said standard.

2. A can opener comprising a base, means for rotatably supporting a can upon said base, said supporting means including a fixed abutment and a movable abutment for rotatably retaining the sides of a can therebetween, means for slidably and guidably securing said movable abutment to said base for rectilinear movement thereon, said means comprising a channel in said base having inwardly inclined side walls, a slide

depending from said movable abutment and slidably retained in said channel.

3. A can opener comprising a base, means for rotatably supporting a can upon said base, said supporting means including a fixed abutment and a movable abutment for rotatably retaining the sides of a can therebetween, means for slidably and guidably securing said movable abutment to said base for rectilinear movement thereon, said means comprising a channel in said base having inwardly inclined side walls, a slide depending from said movable abutment and slidably retained in said channel, a pair of clutch arms pivoted to said movable abutment and having clutch fingers extending into said channel for engagement with said inclined walls.

4. A can opener comprising a base, means for rotatably supporting a can upon said base, said supporting means including a fixed abutment and a movable abutment for rotatably retaining the sides of a can therebetween, means for slidably and guidably securing said movable abutment to said base for rectilinear movement thereon, said means comprising a channel in said base having inwardly inclined side walls, a slide depending from said movable abutment and slidably retained in said channel, a pair of clutch arms pivoted to said movable abutment and

having clutch fingers extending into said channel for engagement with said inclined walls, resilient means urging said fingers into engagement with said walls.
